UNITED STATES PATENT OFFICE

2,371,940

PUMP

Joseph C. Woodford, Spring Lake, Mich., assignor
to John Wood Manufacturing Company, Inc.,
Philadelphia, Pa., a corporation of Delaware

Application April 15, 1944, Serial No. 531,155

6 Claims. (Cl. 103—178)

My invention relates to improvement in pumps, and particularly to hand operated pumps of the direct acting reciprocating piston type.

My improved pump is particularly adaptable for use in dispensing fluids from a container, such as a 55 gallon steel drum, etc., and my pump is adapted to be secured in removable screw threaded connection in the standard screw threaded opening provided in such containers.

One feature of my invention is that the axis of the pump cylinder, piston and piston rod, and operating pump handle are in a substantially horizontal plane and substantially at right angles to the axis of the inlet and outlet of the pump. Such construction enables the user to operate the pump with an easy, natural, horizontal sidearm movement when the pump is installed in the top of a container, say, a 55 gallon steel drum. A receptacle for the fluid being pumped may be supported on the top of the drum, with the opening of the receptacle in registry with the dispensing outlet of the pump.

Another feature of my invention is that my improved pump construction may be economically manufactured and assembled because of its peculiar construction and arrangement.

My invention includes the various novel features of construction and arrangement hereinafter more definitely specified with reference to the accompanying drawings.

Fig. I is a vertical sectional view, partly in elevation, of my improved pump. Fig. II is a right hand end elevation of the structure shown in Fig. I. Fig. III is a vertical sectional view of the structure shown in Fig. I, taken on the line III—III in Fig. I.

Referring to the drawings; the substantially hollow pump base casting 1, preferably unitary, has at its lowermost end an enlarged portion 2 which is provided with the screw thread 3 which is adapted for engagement with the standard screw threaded opening provided in a steel drum (not shown) of standard 55 gallon capacity.

The lower portion of said pump base casting 1 has the internal annular partition flange 5 provided with the screw threaded opening 6 therethrough. The upper end of the fluid inlet pipe 7 is provided with the screw thread 9 and is in rigid screw threaded engagement with the screw threaded opening 6 formed in said partition flange 5. Said inlet pipe 7 depends from the base casting 1 to the lower portion of a fluid container from which fluid is dispensed by the pump. The upper end of said inlet pipe 7 is provided with the valve seat 10 for the ball valve 11 which controls the passage of fluid from the inlet pipe 7 to the chamber 12. Said pump base casting 1 is provided with the vent hole 13, conveniently extending through the side wall of the base casting 1 and below the partition flange 5.

The flared annular discharge throat 15 of said chamber 12 is in continuous open communication with the annular passageway 16 formed between the outer cylindrical casing 17 and the piston cylinder 18 which are in spaced relationship, as shown in Figs. I and III.

As shown in Fig. I, the right hand end of the outer cylindrical casing 17 is provided with the screw thread 20 and is in rigid screw threaded engagement with the internally screw threaded opening 21 formed in said base casting 1. The left hand end of said outer cylindrical casing 17 is provided with the end closure 22 which has an annular flange 23 which is pushfitted into the left hand end of the outer cylindrical casing 17. Said end closure 22 is maintained in rigid fluid tight relationship with said casing 17 by any well known means, such as soldering, brazing, or welding.

20. The right hand end of the pump cylinder 18 is provided with the screw thread 25 which is rigidly engaged with the screw threaded opening 26 formed in the reduced annular flange 27 of said pump casting 1. Said pump casting 1 is provided with the boss 28 which has the drilled opening 29 therethrough forming a bearing for the pump piston rod 30. As shown in Fig. I, the left hand end of said piston rod is provided with the reduced screw threaded portion 32 forming the shoulder 33 for positioning the piston 35 on the end of the piston rod 30. Said piston 35 is maintained in rigid position on the rod 30 by means of the nut 36. Said piston 35 is provided with a series of port openings 37 therethrough and, conveniently, provided with the piston ring 38 which forms a seal with the internal cylindrical surface of the pump cylinder 18. Said piston port openings 37 are normally closed by means of the imperforate valve disc 40 which is spring pressed against the piston 35 by means of the compression spring 41. Said spring 41 is maintained in position by means of the pin 42 which extends through a drilled opening formed in said piston rod 30.

45. As viewed in Fig. I, the right hand end of the opening 29, forming the bearing for the piston rod 30, is provided with a packing gland 45 and packing gland adjusting nut 46 which is in screw threaded engagement with the screw thread opening 47. The right hand end of the piston rod 30 is provided with the screw thread 48 which is in rigid engagement with the screw threaded opening 49 formed in the pump handle 50.

I find it convenient to provide the handle 50 with the opening 51 by which the piston rod 30 may be locked against movement by the insertion of the hasp of a lock through said opening 51 and the opening 52 formed in the lock link 53 which is pivotally mounted on the stud 54 fixed in the boss 55 of the pump casing 1. When it is desired to lock the pump handle and piston rod

assembly to prevent operation of the pump, the lock link 53 is moved counterclockwise from the position shown in Fig. I to a position in which the lock link opening 52 is in registry with the opening 51 formed through the pump handle, and the hasp of a padlock may be readily inserted through the aligned openings 51 and 52 and the padlock locked, thus preventing movement of the pump handle 50 and piston rod assembly connected thereto.

The right hand end of the pump cylinder 18 is in continuous open communication with the outlet chamber 56 formed in the pump casing 1. Said chamber 56 is provided with the screw threaded outlet opening 57 formed in the boss 58. The fluid dispensing nozzle pipe 60 is provided at its lower end with the screw thread 62 which is in rigid engagement with the screw threaded outlet opening 57. The upper end of the dispensing pipe 60 is conveniently bent to an angular position such as is shown in Fig. II, so that the fluid pumped may be readily discharged through the open outlet of the dispensing nozzle 63 into any desirable receptacle positioned beneath said nozzle 63.

Operation

Assuming that the pump is rigidly secured in the top of a steel drum by engagement of the screw thread 3 with the standard screw threaded opening provided in such a steel drum, the inlet pipe 7 will extend to the lower portion of the drum from which the fluid is to be dispensed. Movement of the pump handle 50 to the right, as viewed in Fig. I, will draw liquid from the drum container up through the inlet pipe 7 and cause the ball valve 11 to be moved off its valve seat 10. Liquid will flow through the chamber 12, discharge throat 15, annular passageway 16 and into the left-hand end of the pump cylinder 18 as the pump piston 35 is moved to the right. As the piston 35 is moved to the right through the pump cylinder 18, the port openings 37 in the piston 35 remain closed because the disc 40 is pressed against the piston 35 by means of the compression spring 41. When the piston 35 reaches the end of its stroke at the right hand end of the pump cylinder 18 and the operator then moves the handle 50, piston rod 30 and piston 35 to the left, as viewed in Fig. I, the ball valve 11 will be forced by fluid pressure on to its valve seat 10, thus preventing flow of fluid back through the inlet pipe 7. Movement of the piston to the left, as just described, will place the fluid between the piston and ball valve 11 under such pressure as will cause the valve disc 40 to be opened against the effective forces of its spring 41, and the fluid under pressure will pass through the piston port openings 37, around the open valve disc 40, through the chamber 56 and dispensing nozzle outlet pipe 60 and open outlet of the dispensing nozzle 63 into any desirable receptacle positioned beneath said nozzle 63.

It is obvious that various modifications may be made in my invention without departing from the essential features thereof, and, therefore, I do not desire to limit myself to the specific details of construction and arrangement hereinbefore set forth.

I claim:

1. In a hand operated direct acting reciprocating piston pump, including an inlet pipe, inlet valve, and outlet pipe, a flow passageway from the discharge side of the pump to the out-

let pipe, and a piston and piston rod assembly in operating relation with a piston cylinder; the combination with an outer cylinder in spaced relation with said piston cylinder; of means closing the outer end of said outer cylinder; an open inlet passageway formed between the inner periphery of said outer cylinder and the outer periphery of said piston cylinder; an open chamber passageway between said inlet valve and said inlet passageway; whereby a continuous open communicating passageway is afforded between the inlet side of said piston cylinder and said inlet valve; and a main body casting independently supporting and carrying said inlet and outlet pipes and said piston cylinder and said outer cylinder, said cylinders being supported at one end only from said body casting.

2. In a hand operated direct acting reciprocating piston pump, including an inlet pipe, inlet valve, and outlet pipe, a flow passageway from the discharge side of the pump to the outlet pipe, and a piston rod and piston rod assembly in operating relation with a piston cylinder; the combination with an outer casing in spaced relation with said piston cylinder; of means closing the outer end of said outer casing; an open inlet passageway formed between the inner periphery of said outer casing and the outer periphery of said piston cylinder; an open chamber passageway between said inlet valve and said inlet passageway; whereby a continuous open communicating passageway is afforded between the inlet side of said piston cylinder and said inlet valve, and a main body casting independently supporting and carrying said inlet and outlet pipes and said piston cylinder and said outer cylinder, said cylinders being supported at one end only from said body casting.

3. In a hand operated direct acting reciprocating piston pump, including an inlet pipe, inlet valve, and outlet pipe, a flow passageway from the discharge side of the pump to the outlet pipe and a piston and piston rod assembly in operating relation with a piston cylinder; the combination with an outer casing in coaxial relation with said piston cylinder; of means closing the outer end of said outer casing; an open inlet passageway formed between the inner periphery of said outer casing and the outer periphery of said piston cylinder; an open chamber passageway between said inlet valve and said inlet passageway; whereby a continuous open communicating passageway is afforded between the inlet side of said piston cylinder and said inlet valve; and a main body casting independently supporting and carrying said inlet and outlet pipes and said piston cylinder and said outer cylinder, said cylinders being supported at one end only from said body casting.

4. A pump as in claim 1; wherein said outer cylinder, piston cylinder and piston assembly are supported and carried by said main body casting in a plane substantially at right angles to said inlet and outlet pipes.

5. A pump as in claim 2; wherein said outer casing, piston cylinder and piston assembly are supported and carried by said main body casting in a plane substantially at right angles to said inlet and outlet pipes.

6. A pump as in claim 3, wherein said outer casing, piston cylinder and piston assembly are supported and carried by said main body casting in a plane substantially at right angles to said inlet and outlet pipes.

JOSEPH C. WOODFORD.
